UNITED STATES PATENT OFFICE

HARRY B. HULL, OF DAYTON, OHIO, ASSIGNOR TO FRIGIDAIRE CORPORATION, OF DAYTON, OHIO, A CORPORATION OF DELAWARE

REFRIGERATING APPARATUS

Application filed August 25, 1928. Serial No. 302,043.

This invention relates to improvements in mechanical refrigerators especially those intended for domestic use.

The present application is a continuation in part of my co-pending application, Serial No. 684,256, filed January 3, 1924.

One object of the invention is to provide a refrigerator having a cooling unit in a heat insulated cold compartment and a separate compressor unit in a machinery compartment and means whereby both these units and their operative interconnections may be easily and quickly removed from the cabinet or replaced therein without disturbing the interconnections between said units. By this invention therefore it is possible to completely assemble the apparatus and test the same outside of and independent of the cabinet, and then move said units into their proper compartments in the cabinet without again disassembling or disconnecting said apparatus.

Another object of this invention is to provide a refrigerating apparatus in which portions of the refrigerating system may be removed from the cabinet for inspection or repair while other portions of the refrigerating system remain in the cabinet without disconnecting the refrigerant line which connects said parts.

A more specific object is to accomplish the above results and yet leave the heat insulating wall between the cold and compressor compartments in its fixed place in the cabinet, whereby said wall may be more effectively sealed in place to prevent passage of heat into the cold compartment.

Further objects and advantages of the present invention will be apparent from the following description, reference being had to the accompanying drawings, wherein preferred forms of embodiment of the present invention are clearly shown.

In the drawings:

Fig. 1 is a vertical section, on line 1—1 of Fig. 3 through a refrigerator built according to this invention.

Fig. 2 shows the two refrigerator units and their interconnections (in dotted lines) placed on a stand (in full lines) which is

used to support the units while they are being moved to position in the cabinet;

Fig. 3 is a front elevation of the refrigerator but showing the movable panels removed. This figure also shows in dotted lines the overhanging stand shown in Fig. 2;

Fig. 4 illustrates on an enlarged scale a section on line 4—4 of Fig. 1;

Fig. 5 is a view similar to Fig. 1, but shows a modification wherein the supporting stand is adapted to be moved into the cabinet and forms part of the complete refrigerator;

Fig. 6 is a side elevation of the stand and refrigerator units shown in Fig. 5, when they are removed from the cabinet.

Fig. 7 is a section on line 7—7 of Fig. 5;

Fig. 8 is a front elevation of a further modification showing the central panel covering the pipes and the lower panel covering the compressor compartment removed;

Fig. 9 is a section on line 9—9 of Fig. 8, but shows the central panel in place and the doors closed.

Fig. 10 is a vertical cross sectional view of an apparatus embodying features of my invention.

Fig. 11 is an elevation of a portion of the refrigerating apparatus shown in Fig. 10, the apparatus being placed on a stand ready for placing the refrigerating system adjacent the cabinet for final assembly at the place of use or at any other convenient place;

Fig. 12 is a diagrammatic view of the refrigerating system shown in Figs. 10 and 11;

Fig. 13 is an elevation of the lower portion of the rear portion of the apparatus shown in Fig. 10;

Fig. 14 is a side elevation of the base for the refrigerant liquefying unit;

Fig. 15 is an end elevation of Fig. 14;

Fig. 16 is a cross sectional part of a refrigerating apparatus slightly modified, which embodies features of my invention; and

Fig. 17 is a diagrammatic side view of a portion of the apparatus shown in Fig. 16 shown attached to a stand ready to be carried to and placed adjacent the cabinet for

the final assembly partly or wholly within the cabinet.

Similar reference characters refer to similar parts throughout the several views of the drawings.

Referring to the drawings, 10 is the outer cabinet which may be made of wood or any other suitable material. The lower portion of the cabinet is partitioned off and forms 10 the compressor compartment 11 for the location of the compressor unit 12, comprising in the embodiment shown an SO₂ compressor and condenser, the latter of which receives the compressed refrigerant from the compressor, condenses and stores the liquid refrigerant in the well known manner. The electric motor for operating the compressor, and the various automatic mechanisms connected therewith are also located in the compartment 11.

The upper part of the cabinet is provided with substantial heat insulating walls 15. In the form shown in Figs. 1 to 4 the upper heat insulated compartment is divided by 25 the partition walls 16 into a central cooling compartment 17 and a food compartment 18, on each side thereof. The central compartment 17 contains the cooling unit 20, which in the embodiment shown, comprises a header tank 23 and a series of evaporating coils 24 in which the liquid SO₂ is evaporated or boiled and thus absorbs heat from the air circulating around the coils. The air within the upper heat insulated compartment 30 circulates downward in the central cooling compartment 17 and upward through the two food compartments 18, again entering compartment 17 at the top thereof. The liquid SO₂ passes from the 35 compressor unit 12 to the cooling unit 20 through a duct 21, and the vaporized SO₂ passes back from the cooling unit 20 to the compressor 12 through the duct 22. These ducts 21 and 22 may be called the operative 40 interconnections between the compressor unit 12 and the cooling unit 20, or may be called the refrigerant line.

The front wall of the cooling compartment 17 between the lower portion of the 45 large doors is provided with a removable panel 25 of such dimensions as to permit the cooling unit 20 to readily pass through the opening when the panel is removed. The front wall of the compressor compartment 50 11 is likewise provided with a removable panel 26 which permits the compressor unit to pass through the opening into the compressor compartment when the panel is removed. These two removable panels 25 and 55 26 overlap one another as clearly shown in Fig. 1. The two ducts 21 and 22 are looped around as clearly shown in the drawings so as to pass from compartment 11 to compartment 17 immediately in front of the cross 60 frame member 30 of the cabinet. Prefer-

ably this cross member 30 is grooved to receive the ducts 21 and 22, so that the removable panel 25 will lie flat up against said member and thus effectively seal the compartment 17 from the outside temperature. The heat insulating floor 31 is continuous 70 across the entire cabinet and is permanently secured in place, being effectively sealed at the back and sides to the wall 15 and at the front to the cross frame member 30.

It will be obvious from the drawings and above description that the cabinet may be entirely completed and then the compressor and cooling units with their interconnections in assembled form may be inserted in the cabinet by removing the panels 25 and 26. 75 In order to facilitate the placing of the refrigerating mechanism in the cabinet a stand 40 is preferably provided which supports the cooling unit approximately at the level of the floor of the cooling compartment and the compressor unit approximately at the level 80 of the floor of the lower compressor compartment. The units are placed upon the stand 40 approximately in the relative position shown in Figs. 2 and 3, the ducts 21 and 22 looping around the end of the overhanging top support 41 (see Fig. 3). The refrigerating mechanism or system after being placed on the stand 40 may be moved adjacent the cabinet to a position convenient for inserting the units within the cabinet. It will now be clear that both units with their interconnecting ducts may be easily moved from the stand 40 over into their respective compartments 85 in the cabinet, the ducts 21 and 22 entering the vertical groove provided therefor in the member 30. Preferably some suitable sealing material, for instance hydrolene, is used to completely fill up the space around the ducts in said groove, after which the panel 25 is secured in place by screws extending into the cross members 30 and 32 and thus covers the groove. The panel 26 is next secured in place by one or more lugs 45 at the bottom and one or more screws 46 at the top extending into the metal angle clip 47 in turn secured to member 30. In the drawings the removable panel 25 is shown provided with a small hinged door 50 which permits access 90 to the small drawers 51 located at the center of the expansion coils 24. The two food compartments 18 have separate doors 52 provided therefor as clearly shown in Fig. 3. Since the evaporating coils 24 are considerably 95 colder than any other surface within compartments 17 and 18, moisture from the circulating air will be condensed upon said coils 24 until the relative humidity is brought so low that all other surfaces within these compartments will remain dry. The coils 24 are provided with drip troughs 53, which collect the condensed water and discharges it 100 through the drain pipe 54.

In the modifications shown in Figs. 5, 6 and 105

7 the refrigerator cabinet is slightly modified in order to permit the supporting stand 40' together with the cooling unit 20 and the compressor unit 12 with their interconnections to be housed within the cabinet. The 5 stand 40', is so constructed that the upper support 41' for the cooling unit 20 is held by a single upright member 60 and has pivoted thereto the brace member 61 which aids in supporting the overhanging weight of the 10 cooling unit 20. The units 12 and 20 are arranged in substantially the same relative positions as in the modifications described above. The stand 40' is preferably provided with rollers or casters 62 to render the assembled 15 units more easily portable when outside the cabinet, as well as to facilitate the movement of the stand and units and into or out of the cabinet. In this modification the floor 31' of the cooling compartment 17 is cut away as 20 clearly shown in Figs. 5 and 7, to permit the passage of the upright member 60. The block 66 is rigidly attached to the removable panel 65 and is removable therewith. The removable panel 67 for the compressor compartment 25 is held in place at the bottom by the lugs 68 and at the top is screwed to the small metal angle clips 69 secured to a stationary part of the cabinet on either side of the removable panel 65. The top of panel 67 laps over the 30 lower edge of panel 65 thus holding the lower edge of panel 65 rigidly in place (see Fig. 5). The top of panel 65 is held in place by being screwed to the cross member 32, as in 35 the previously described modification.

35 It will now be clear that by removing panels 67 and 65, the stand 40' together with the refrigerating units 20 and 12 in assembled form may be moved into place in the cabinet. As soon as the short leg 63 for the 40 upper support 41' rests upon the floor 31' and the brace 61 is released from the lug 64 and allowed to swing down alongside of upright 60 (see Fig. 5). This permits the upright 60 to be moved snugly up into the recess in the floor 31' provided therefor. The 45 ducts 21 and 22 lie immediately in front of upright 60 as clearly shown in Fig. 7. The block 66 has a recess 70 cut therein for the ducts 21 and 22, which recess is preferably 50 sealed up with suitable sealing material after the units are moved into the cabinet and the panel 65 has been secured in place. When it is desired to remove the refrigerating units 55 from the cabinet it is necessary only to break the sealing material around the recess 70 and remove the panels 65 and 67 after which the stand 40' with the units may be rolled out. It is thus clear that repairs may be 60 readily made or new units substituted at any time without either marring the cabinet in any way or disassembling the refrigerating apparatus.

In the modification shown in Figs. 8 and 9 65 the cooling unit 20 is located in a compartment

ment 80 provided therefor in the upper left hand corner of the cabinet when viewed as shown in Fig. 8. The compressor unit 12 is located in the lower compartment 11 as in the two modifications above described. A small food compartment 81 is located between the compartment 80 and the compressor compartment 11. A large food compartment 82 occupies the space on the right side of the cabinet above the compartment 11. 70 Of course the compartments 80, 81 and 82 are provided with heat insulating walls and suitable partitions between the compartments to give the desired convection currents for the circulation of the air past the cooling unit 20 and through the food compartments. In this modification the central post 85 of the cabinet is grooved out at 86, as clearly shown in Figs. 8 and 9, to provide a passageway for the ducts 21 and 22 from the compartment 11 to the compartment 80. A removable cover panel 87 fits over the grooved out portion of the post 85 and screwed to the post 85 (see Fig. 9). Fig. 8 shows the cover panel 87 removed and the doors to the compartments 80, 81, and 82 all open. It will be obvious from Fig. 8 that the two units 12 and 20 with the ducts 21 and 22 connecting them in operative form may be moved into or out of the cabinet in a manner similar to that described for the previous modifications. Of course it is preferable that the space around the ducts 21 and 22 where they pass from the groove 86 into the compartment 80 be sealed with some suitable material such as hydrolene. After the refrigerating apparatus is in its proper position in the cabinet, the cover plate 87 and the cover panel for compartment 11 are secured in place. The duct 54' is the drain pipe for the moisture condensed upon the cooling unit 20 but it is not attached to said unit and is not removable with the refrigerating apparatus.

In all three of the modifications described herein other ducts or connections such as thermostat lines or pressure ducts may parallel the ducts 21 and 22 in order to pass from the cooling compartment to the mechanism compartment. Preferably all of the ducts are of somewhat flexible tubing to permit them to move to their exact positions when moving the refrigerating apparatus to within the cabinet.

In general, another refrigerating apparatus (see Fig. 10) embodying features of my invention comprises a cabinet generally designated as 120 in which a refrigerating system may be inserted. In general, the refrigerating system preferably comprises several members including an evaporator generally designated as 121, a refrigerant liquefying unit generally designated as 122 and a system operation control mechanism generally designated as 123. These members of the refrigerating system are connected by 125 130

flexible lines which permit the insertion of these members into the cabinet independently of each other without disconnecting the lines. The lines comprise one form of a refrigerant 124 and an electric line 125.

Referring more particularly to Fig. 12, the evaporator 121 receives liquid refrigerant from a portion of the refrigerant liquefying unit 122. More specifically, the evaporator 121 receives refrigerant from the liquid receiver 127 through a pipe 128 of the refrigerant line 124. The liquid refrigerant in pipe 128 is expanded by means of an expansion valve 129 before entering coils 130 of the evaporator 121. After passing through the coils 130, the refrigerant returns to the liquefying unit through pipe 129a of the refrigerant line 124. Preferably the refrigerant returns to the compressor 131 of the refrigerant liquefying unit 122 and, preferably, the refrigerant enters the crankcase of the compressor. The refrigerant, after being compressed in the compressor 131 passes to a condenser 132 where the refrigerant is liquefied and is stored in the liquid receiver 127 for use in the evaporator 121. The refrigerant liquefying unit also includes a motor 133 which drives the compressor 131, for instance by means of the belt 134. The electric motor 133 is started and stopped by means of the snap switch 135 of the system control device 123, which switch 135 is operated by the expandable bellows 136 operating through a lever mechanism 137 in accordance with temperature conditions in a thermostatic bulb 138. The snap switch 135 stops and starts the motor through the medium of the electric line 125. In Fig. 12 these parts are shown diagrammatically mounted on the stand 139 for carrying the refrigerating system to the cabinet. Loops 140 are shown in the refrigerant line and in the electric line which are intended to show diagrammatically that these lines are of sufficient length to permit the members of the refrigerating system to be moved relatively to each other in order that they may be installed in the cabinet 120 without disconnecting the lines but with a relative movement to each other necessary in order to install the parts properly. In actual practice the lines need not be looped since an actual loop might cause a kink. As shown in Fig. 10, the refrigerant liquefying unit 122 may be placed either in front or behind the cabinet without disturbing the evaporator 121. This is accomplished because of the length of the refrigerant and electric lines which are shown looped at 140 in Fig. 1. The dotted representations of the refrigerant liquefying unit 122 indicate positions which the unit may be placed in either during final assembly or after final assembly for adjustment of the unit or for repair of the same.

The stand 139 may be placed immediately

behind the cabinet 120 to place the refrigerant liquefying unit somewhat in the position shown in dotted lines in Fig. 10. That is, the stand would be placed with its longitudinal axis parallel with the back of the cabinet and with the refrigerant liquefying unit immediately behind its proper compartment. The evaporator 121 may then be unbolted from the stand 139 and may be placed in the upper compartment of the cabinet in the position shown in Fig. 10. The refrigerant liquefying unit may then be unbolted from the stand and may be inserted into the cabinet in the position shown in full lines in Fig. 10.

The details of these parts may be varied, but as a specific embodiment, the evaporator 121 is mounted on an insulated platform 141 by means of metallic loops 142 which depend from the insulated platform 141. Within the loops 142 are ice tray sleeves 143 for receiving the ice trays 144. A suitable front cover 145 is positioned in front of the metallic loop 142. Around the sleeves 143 is wound the coil 130 for the passage of the expanded refrigerant. The expansion valve 129, as shown herein, is attached to the back of the evaporator 121 and may be of any suitable type. In this specific embodiment the valve is of the diaphragm type in which one side of the diaphragm is subjected to the pressures of an artificial atmosphere maintained in a bulb 146 in order to prevent frosting of the diaphragm. The other side of the diaphragm is subjected to refrigerant pressures so that the valve maintains any desired pressures in the coil 130 of the evaporator. For convenience, the metallic loops 142 are used to support the evaporator on the stand 139 and when so supported, the evaporator is secured to the stand by means of one or more bolts 147 passing through the insulated platform 141 and holding the evaporator securely to the stand 139. The refrigerant liquefying unit is also preferably bolted by bolts to the other end of the stand 139 for convenience in effecting the final assembly. When the units on the stand 139 are to be carried in a manner in which damage may be caused to the units a suitable box may be inverted over the units, and the edges of the box may be nailed to the stand 139. Thus the units can be carried without danger of accidental damage to the parts.

The system operation control mechanism 123 containing the switch 135 may be mounted along with the evaporator, if desired. In this particular embodiment the switch 135 is mounted on the top of the insulated platform 141 together with the lever mechanism 137 and the bellows 136. These are all encased in a suitable cover for protecting the parts as indicated in Fig. 10. The thermostatic bulb 138 is mounted inside of the cabinet 120 adjacent the evaporator 121 as shown in Fig. 10 with a suitable pipe connection 150 for con-

necting the same to the bellows 136. The switch 135 is connected with the electric motor 133 through the electric line 125 which is clamped together by means of clamps 151 for convenience in handling and for preventing kinks in the lines.

The refrigerant liquefying unit, as a specific embodiment, is mounted on a platform. In general the platform is made of side metallic angle irons 155 joined by cross metal members 156 (see Figs. 13, 14 and 15). The liquid receiver 127 is a tubular member and is also used to join the side members 155. The cabinet 120 is provided with angle irons 157 having notches 158 cut therein. The flanges of the members 155 thus rest on the horizontal flanges of the members 157 and the platform is secured in place by passing a rod through notches 158a in the side pieces 155 and the notches 158. The other end of the member 155 is secured by clamps 159 hooked over the cross pieces 156 and secured by means of hook bolts 160 hooked in proper holes in the members 157. Thus merely by loosening the nuts 161 of the bolts 160, the refrigerant liquefying member 122 may be removed from the cabinet.

The exact details of the refrigerant liquefying member may be varied, but as herein shown, it includes the motor 133 and compressor 131 mounted on a flexibly supported platform 162 (see Fig. 10) in such a manner as to permit the compressor and motor to vibrate freely about the center of oscillation without greatly disturbing the remainder of the apparatus. This flexible mounting may be clamped down when the apparatus is to be carried. The condenser 132 (see Fig. 11) is mounted over the receiver 127 and is preferably provided with vertical fins 163 in order to increase the heat exchanging area. The connections between the compressor and condenser are partly looped, as at 164, in order to permit the proper play of the compressor in relation to the condenser.

In Fig. 10 the evaporator is shown as insertible through the top, preferably by lifting off the cover 170 of the cabinet 120, and then lowering the evaporator on to the top 171 of the frame of the cabinet. However, the evaporator may be made insertible through any other portion of the cabinet. In Fig. 16 the evaporator 121a is shown insertible through the back of the cabinet 120a. In this case the insulated platform 141a forms part of the back of the cabinet. As shown in Fig. 17 the evaporator 121a is mounted on the stand 139a by any suitable means such as by placing blocks 174 under loops 142a and by bolting the unit to the stand. Brackets 175 extending from the insulated platform 141a support the unit 121a.

In the manufacture of the refrigerating apparatus, the cabinet may be manufactured separately from the refrigerating system.

The refrigerating system is preferably manufactured, assembled, tested and mounted on stand 139 independently of the cabinet. The refrigerant is charged into the system before final assembly in the cabinet and the system is made ready for operation with the exception of installation in the cabinet. The final assembly of the refrigerating system in the cabinet may be made by relatively unskilled labor, since no difficult connection of the refrigerating system need to be made in the final assembly. For example, at the final assembly, the evaporator 121 may be removed from the stand 139 and may be lowered into the cabinet 120. Thereafter the refrigerant liquefying unit 122 may be inserted into the lower compartment of the cabinet 120 and may be secured in place by means already described. The refrigerant liquefying unit 122 can be removed from the cabinet without disturbing the evaporator and without disconnecting the lines if it should be necessary to adjust the unit or make minor repairs in the unit at the place of use. The evaporator also can be removed from the cabinet without disturbing the liquefying refrigerant unit. Thus it is apparent that this is a refrigerating apparatus which can be completely assembled and tested independently of the cabinet, and then moved into proper compartments of the cabinet without again disassembling or disconnecting the refrigerating apparatus.

While the form of embodiment of the invention as herein disclosed, constitutes a preferred form, it is to be understood that other forms might be adopted, all coming within the scope of the claims which follow.

What is claimed is as follows:

1. In a refrigerator, a cabinet having an insulated partition dividing same into a cooling compartment and a machine compartment, a removable refrigerating device comprising a cooling unit in one of said compartments, a refrigerant medium circulating unit in the other of said compartments, operative interconnections between said units, said cabinet including movable wall means permitting the withdrawal of said units from the cabinet in planes substantially parallel with the partition while the operative interconnections therebetween are maintained.

2. In a refrigerator, a cabinet having a partition dividing same into a compartment containing a cooling unit, and a compartment containing a compressor condenser unit, operative interconnections between said units looped around said partition, said cabinet including movable wall means permitting the insertion in said cabinet of said units and interconnections in assembled form.

3. In a refrigerator, a cabinet having a partition dividing same into a compartment containing a cooling unit and a compart-

ment containing a refrigerant medium circulating unit, operative interconnections between said units extending across the edge of said partition, said cabinet including movable wall means permitting the insertion in said cabinet of said units and interconnections in assembled form.

4. In a refrigerator, a cabinet having a partition dividing same into a compartment containing a cooling unit and a compartment containing a refrigerant medium circulating unit, operative interconnections between said units extending across the edge of said partition, said cabinet including movable wall means permitting the insertion in said cabinet of said units and interconnections in assembled form in planes substantially parallel to said partition.

5. In a refrigerator, a compartment containing a removable cooling unit, a machine compartment containing a removable refrigerant medium circulating unit, operative interconnections between said units, the wall of the refrigerator having openings to permit the insertion in said compartments of said units and interconnections in assembled form, and removable panel means for said openings.

6. The combination with a refrigerator box having an insulated partition dividing same into a cooling compartment and a machine compartment; of a sub-assembly including a cooling unit, a refrigerant medium circulating unit, operative interconnections between said units, and a stand having means extending along the edge of the partition and into said compartments for supporting said units within their respective compartments.

7. The combination with a refrigerator box having a partition wall dividing said box into a cooling compartment and a machine compartment; of a sub-assembly including a cooling unit, a refrigerant medium circulating unit, operative interconnections between said units, and a stand having means adapted to extend into the machine compartment for supporting the circulating unit therein and means extending into the cooling compartment for supporting the cooling unit in the cooling compartment, the walls of the compartments having openings permitting the insertion in said compartments of said subassembly in planes substantially parallel with the partition.

8. In a refrigerator, a pair of separated chambers, a compressor element and a receiver element in one of said chambers mounted independently of the wall between the chambers, a cooling element in the other of said chambers, an unbroken pipe extending between said receiver element and said cooling element, an unbroken pipe extending between said cooling element and said compressor element, both of said pipes ex-

tending through the wall between the chambers, and means whereby all of said elements may be removed as a unit from said refrigerator, free of the said wall, while maintaining said pipe connections intact.

9. In a refrigerating apparatus, the combination of a refrigerator box structure having an upper cooling compartment and a lower machinery compartment, an evaporator disposed in the cooling compartment, a compression mechanism disposed in the machinery compartment, a condenser, and a common supporting structure for the evaporator and the compression mechanism, said supporting structure together with the evaporator and the compression mechanism being removable as a unit from the refrigerator box structure.

10. In a refrigerator, a cabinet having an open front, an insulating wall in said cabinet separating the interior of the same into two compartments and having an edge exposed at said front, a door for each compartment cooperating with said exposed edge of said wall to close said open front, a cooling unit removably secured in one of said chambers, a heat dissipating unit removably secured in the other of said chambers, tubing connecting said units, a notch in said exposed edge of said wall for the passage of said tubes, and a removable filler block in said notch embracing the walls thereof and said tubing, said doors contacting against the outer edge of said filler block when in closed position.

11. In a refrigerator, a cabinet having an open front, an insulating wall in said cabinet separating the interior of the same into two compartments and having an edge exposed at said front, a door for each compartment cooperating with said exposed edge of said wall to close said open front, a cooling unit removably secured in one of said chambers, a heat dissipating unit removably secured in the other of said chambers, tubing connecting said units, a notch in said exposed edge of said wall for the passage of said tubing, and a removable filler block in said notch embracing the walls thereof and said tubing, said doors contacting against the outer edge of said filler block when in closed position.

12. In combination, a refrigerator cabinet having an insulated partition dividing the same into upper and lower compartments, a removable refrigerating device comprising cooling means in one of said compartments, heat dissipating means in the other compartment, operative interconnections between said cooling and heat dissipating means, said cabinet including movable wall means permitting the withdrawal of said cooling and heat dissipating means from the cabinet in planes substantially parallel with the parti-

tion while maintaining the operative interconnections therebetween.

13. In combination, a refrigerator cabinet having upright walls and an insulating partition dividing the cabinet into upper and lower compartments, a removable refrigerating device comprising cooling means in one of said compartments, heat dissipating means in the other of said compartments, operative interconnections between said

cooling and heat dissipating means, the front wall of the cabinet having removable portions for permitting withdrawal of said cooling and heat dissipating means from their respective compartments in planes substantially parallel with the partition while maintaining the operative interconnections between said cooling and heat dissipating means.

20 14. In a refrigerator, a cabinet having an insulated partition dividing same into a cooling compartment and a machine compartment, a removable refrigerating device comprising a cooling unit in one of said compartments and a refrigerant medium circulating unit in the other of said compartments, operative interconnections between said units extending across the edge of said partition, panel means covering the edges of the partition and the interconnection at the edge, said panel means being removable permitting the withdrawal of said device with the interconnections in assembled form.

35 15. In a refrigerator, a cabinet having a cooling compartment and a machine compartment; and a sub-assembly including a heat absorbing element, a heat dissipating element operatively connected with the heat absorbing element, and a stand having means for supporting the heat absorbing element in the cooling compartment and for supporting the heat dissipating element in the machine compartment.

45 16. In a refrigerator, a cabinet having a cooling compartment; and a sub-assembly including a heat absorbing element, a heat dissipating element, and a stand having means for supporting the heat absorbing element in the cooling compartment and for supporting the heat dissipating element outside the said compartment.

55 17. In a refrigerator, a cabinet having a partition wall dividing same into a cooling compartment and a machine compartment; and a sub-assembly including a heat absorbing element and a heat dissipating element operatively connected with the heat-absorbing element, and a common support extending on each side of the partition and having means for supporting the heat absorbing element in the cooling compartment and for supporting the heat dissipating element in the machine compartment.

65 18. In a self contained mechanical refrig-

erator having a cabinet having superposed compartments open at one side; a unitary mechanical refrigerating apparatus including a frame entirely supporting an evaporator and machinery in different elevations for association with different compartments, said apparatus being insertible laterally into said cabinet, and a movable closure for closing the opening leading to the refrigerated compartment.

19. The combination with an insulated refrigerating compartment having a horizontally disposed wall and a door opening, of a notch projecting into the horizontally disposed wall immediately adjacent the aforesaid door opening, a machine compartment arranged externally of the refrigerating compartment beyond the horizontally disposed wall, a machinery base arranged within the machine compartment, a refrigerant condensing unit secured to and supported by the latter, a refrigerant evaporating unit support carrying the aforesaid base and projecting into the interior of the refrigerating compartment through the notch in the horizontally disposed wall, a refrigerant evaporating unit in the interior of the refrigerating compartment connected to the aforesaid support, and means for circulating refrigerant fluid between the evaporating unit and the condensing unit, said evaporating unit, condensing unit, machinery base, and evaporating unit support being insertible into and removable from the refrigerating and machinery compartments by movement in planes parallel to the aforesaid horizontally disposed partition.

20. The combination with an insulated refrigerating compartment having a plurality of vertically disposed walls closed by horizontally disposed walls at opposite ends of the latter, a machinery compartment arranged externally of the refrigerating compartment beyond one of the aforesaid horizontally disposed walls, a refrigerant condensing unit disposed in the machinery compartment, a refrigerant evaporating unit disposed in the refrigerant compartment, a rigid support extending in close proximity to one of the walls of the refrigerating compartment, said refrigerant condensing and evaporating units being connected to the support adjacent the opposite ends thereof.

21. In a refrigerator, a pair of chambers provided with an insulating wall therebetween, compressing, condensing and receiving means in one of said chambers, a cooling element in the other of said chambers, a notch in an exposed edge of said wall, an unbroken pipe connecting said means to said cooling element, another unbroken pipe connecting said cooling element to said means, said pipes passing through said notch, and means closing said notch.

22. In a refrigerator, a cabinet, a wall

therein separating the interior thereof into two chambers, compressing, condensing and receiving means in one of said chambers secured to a unitary removable base, a cooling unit in the other of said chambers, an opening in said wall, a tube passing through said opening connecting said means to said cooling unit, another tube passing through said opening connecting said cooling unit to said means, and means closing said opening removable from said wall in the direction of the plane thereof whereby said units may be removed from said cabinet without disconnecting said tubes.

15 In testimony whereof I hereto affix my signature.
